UNITED STATES PATENT OFFICE.

STANLEY L. WILCOX, OF NEW YORK, N. Y.

DESIGN FOR A SUPPORTING-BASE FOR SALT AND PEPPER SHAKERS.

48,234.

Specification for Design.

Patented Nov. 30, 1915.

Application filed August 25, 1913. Serial No. 786,623. Term of patent 7 years.

To all whom it may concern:

Be it known that I, STANLEY L. WILCOX, a citizen of the United States of America, and resident of the borough of Brooklyn, in the county of Kings, city and State of New York, have invented a certain new, original, and ornamental Design for a Supporting-Base for Salt and Pepper Shakers, of which the following is a specification, reference being had to the accompanying drawing, forming part thereof.

The figure is a perspective of a supporting base for salt and pepper shakers, showing my new design.

I claim:

The ornamental design for a supporting base for salt and pepper shakers as shown.

STANLEY L. WILCOX.
